UNITED STATES PATENT OFFICE.

GEORGE SAMUEL HENRITZY, OF HAZLETON, PENNSYLVANIA.

WINDOW VENTILATOR.

Application filed January 6, 1923. Serial No. 611,059.

This invention relates to ventilators and has particular reference to those ventilators which are removable.

The primary object of my invention is the provision of an improved ventilator having a flexible body member including a frame which is foldable so that the flexible body portion will be in a plane and the frame members will lie together and substantially in parallel lines.

Another object of my invention is the provision of an improved ventilator having a foldable frame at the top which, when in place, will hold its flexible body portion taut at its front and sides.

Still another object of my invention is the provision of a folding ventilator which is attached to a roller and provided with a folding frame, the flexible body portion and frame being so constructed that the flexible body may be folded so that all the parts will lie flat together and the frame parts will have their axes parallel, and close together, whereby the ventilator may be rolled on the roller similar to the manner of rolling a shade.

Still another and further object of my invention is the provision of a ventilator which can be folded and rolled and which is provided with a mosquito bar which will prevent the admission of flies and mosquitoes through the ventilator and which can be folded and rolled with the ventilator.

Referring to the drawing wherein a preferred embodiment of my invention is illustrated,

Fig. 1 is a perspective view of my ventilator without the mosquito bar and showing the position of the holding box in dotted position.

Fig. 2 is a view of the structure shown in Fig. 1 but in folded position ready to roll.

Fig. 3 is a detail view of the connection for holding the ventilator in place.

Fig. 4 is a perspective view of the ventilator showing the mosquito bar installed and

Fig. 5 is an enlarged detail cross section on the line 5—5 of Fig. 4 showing the manner of attaching the mosquito bar.

Fig. 6 is a detail view similar to Fig. 5 but taken at a point distant from the hinge on line 6—6 of Fig. 4.

Fig. 7 is a perspective view of the ventilator after it has been folded and rolled.

Fig. 8 is a view of a modified form of my improved ventilator holder.

Fig. 9 is a cross section on the line 9—9, 55 Fig. 8 but with the ventilator rolled.

Fig. 10 is an end view of the ventilator holder.

Fig. 11 is a cross section on the line 11—11 of Fig. 8. 60

In the drawing, like reference characters refer to similar parts throughout the several views.

10 designates the window frame, to which the ventilator is shown attached. A spring roller 12 is provided with brackets 13 which are mounted on the window frame. Attached to the roller is a strip 14 of flexible material which is rolled thereon. This strip 14 may be of varied length depending upon 70 how much vertical adjustment is desired. Above the part 14 is a flexible front portion 15 which, when the ventilator is in place, extends away from the window to conduct the air toward or away from the window as the case may be. 75

At the sides of the part 15 are two angular pieces 16, 17 of flexible material which occupy the space between the sides of the part 15 and the window frame. At the top of the ventilator and the edge of the parts 15, 16, 17, is a frame 18 which has hinges located at the points 19 and 20 where the upper edges of the parts 16 and 17 meet the ends of the upper edge of the part 15. The hinges at the points 19, 20 are so arranged and the parts 16 and 17 so shaped that when the parts 16 and 17 and the parts of the frame 18 at their upper edges are folded inward on the part 15, the frame parts at the upper edges of the parts 16 and 17 will lie adjacent the frame part at the upper edge of the part 15. 80

This construction is to facilitate the rolling of the curtain upon the roller 12 in a manner to be described. At the inner or window ends of the frame and adjacent the upper corners of the parts 16 and 17 are placed suitable securing means for holding the ventilator in place. Figure 3 shows such a means. The hook 21 is rigid 90

with the end of the frame and extends outward from the frame and then downward substantially parallel with the window frame edge of the side parts 16 and 17. A socket 22 is provided for attachment to the window 100

frame to receive the hook 21. It is to be noted that, because of the shape of the hook 21 and its receiving socket 22, the portion 15 of the ventilator will be held taut and in its proper place. Two or more pairs of sockets 22 may be provided as shown in Figure 1, to provide for adjusting the ventilator at different heights.

Referring now particularly to Figures 4 10 and 5, 30 designates a mosquito bar which is shown attached to the ventilator for preventing flies and mosquitoes from entering the room through the ventilator. At the upper edge of the portion 15 of the ventilator are 15 provided hinges 31 for securing the mosquito bar to the ventilator. These hinges 31 are provided with loops 32 which receive the wire 33 which constitutes a part of the hinge and is received by the fold 34 at the edge of the 20 mosquito bar edge as shown in Figure 6. This fold 34 may be of felt or other suitable material and receives and holds the edge of the mosquito bar.

The mosquito bar is bound also at the sides 25 at 35, 36 with a flexible material as felt and has a wider binding or flap 37 adjacent the window for making tight the bar at this point. If desired, hooks 38 and eyes 39, in the side parts 16, 17, may be provided to hold 30 the parts 16, 17 against the window frame.

Referring now particularly to Figures 8, 9, 10 and 11, 14 designates the strip of the ventilator attached to the roller as shown in Figs. 1 and 2. The ventilator holding box 40 is intended to be used in place of brackets 13 of Figs. 1, 2 and 4 where desired. This ventilator holder box 40 is held in place on the window sill by the screws 41. At the left end of box 40 is a hole for the round pintle of the 40 roller. This left end is shown as integral with the body of the box 40. At the right end of the box is a door 42 hinged at 43. This door is provided with an opening for the flat non-revolving shaft of the spring roller, as 45 shown at 44 in Fig. 10. On the top of the box 40 is a cover 45 which is hinged to the box as at 46. The outer edge of the cover 45 comes short of covering the opening just a sufficient distance to permit of the portion 14 of the ventilator passing through thereat, when the cover is closed. In this way, the cover 44 holds the lower portion 14 of the ventilator close to the window frame and prevents the admission of flies and mosquitoes 50 underneath the roller. In Fig. 9 is shown the ventilator folded and rolled, the frame 18 being indicated.

At the front of the box adjacent the door 60 42 is a spring catch 47 which is illustrated in the enlarged view, Fig. 11. The spring catch has a detent member 48 which passes through openings 49 and 50 in the door 42 and the box 40, respectively. A button 51 is provided to release the detent from the openings 49, 50, by 65 pressing inwardly thereon.

When the ventilator holding box 40 is used instead of the brackets 13, the ventilator is provided not only with a means for holding its lower portion close to the window frame when in position, but is also kept from dust 70 when not in use. In addition to these features, insects are prevented from getting past the ventilator under the roller.

When it is desired to fold the ventilator, it is only necessary to fold the mosquito bar (if attached) over to the outside as shown in dotted lines on Fig. 5, release the hooks 21, fold the sides 16 and 17 against the portion 15 of the ventilator and then permit the ventilator to roll on the roller 12. It is then out of the 80 way; yet it is available for instant use if desired. The ventilator in this folded and rolled position is shown in Fig. 7.

If the ventilator is provided with the box 40, the cover 45 is first raised until it is rolled, whereupon the cover is lowered to its closed position.

While I have described an embodiment of my invention in detail, I desire to have it understood that I do not limit myself to the exact form shown, and that modifications and changes may be made without departing from the spirit of my invention and within the scope of the appended claims.

Having described my invention, what I claim is:

1. A ventilator for windows comprising a flexible body portion comprising a front and sides and a foldable frame for and secured to the respective parts of the body portion, the frame portions being foldable in such a manner that their axes are adjacent and parallel and so correlated to the body portion that when folded will bring the portions of body portion flat and adjacent each other and means at the inner ends of the side frame portions for supporting the frame from the window casing and holding the body portion taut.

2. A ventilator for windows comprising a roller, a flat flexible portion attached to the roller, a front portion and side portions attached to the flat flexible portion and forming a guide for the air, the tops of each of the side portions forming an angle with its edge attached to the front portion, substantially equal to the angle between the top of the front portion and its edge attached to the side portion, stiffening means at the upper edge of the ventilator and means at the inner ends of the sides of the stiffening means for supporting the same and for holding the body portion taut.

3. A ventilator comprising a roller, a body portion having front and side portions attached to the roller for guiding the air, an insect bar secured to the body portion and forming a closure, against insects, for the opening of the ventilator, the sides of the ventilator and the bar being foldable on the

front portion whereby the whole may be rolled upon the roller.

4. A ventilator for windows comprising a roller, front and side portions attached to the roller for guiding the air, an insect bar, the bar forming a closure, against insects, for the opening of the ventilator, a holder for the
5. ventilator roller, having an enclosure for receiving the ventilator when rolled and for preventing the passage of insects therebelow ¹⁰ when the ventilator is in operative position.

In testimony whereof I hereunto affix my signature.

GEORGE SAMUEL HENRITZY.
